UNITED STATES PATENT OFFICE.

THOMAS ALLSOP AND WALTER W. SIBSON, OF PHILADELPHIA, PENNSYLVANIA,
ASSIGNORS TO THE PHILADELPHIA DRYING MACHINERY COMPANY, OF
PHILADELPHIA, PENNSYLVANIA, A CORPORATION OF PENNSYLVANIA.

DRYING-MACHINE.

1,360,705.

Specification of Letters Patent. Patented Nov. 30, 1920.

Application filed September 4, 1919. Serial No. 321,566.

To all whom it may concern:

Be it known that we, THOMAS ALLSOP and WALTER W. SIBSON, citizens of the United States, residing in the city and county of Philadelphia and State of Pennsylvania, have invented certain new and useful Improvements in Drying-Machines, whereof the following is a specification, reference being had to the accompanying drawings.

The invention relates to drying machines ordinarily known as the tunnel type, and more especially to that class of such machines particularly adapted for drying 15 china, porcelain or similar products of manufacture, but which may be employed with equal advantage for other purposes.

The invention is directed to a drying machine interiorly divided into a series of 20 zonal sections through which the articles, to be dried, are successively advanced, and in which it is possible to maintain different atmospheric conditions, so that the drying may be effected in a gradual manner.

The invention is further directed to means 25 whereby the drying medium is circulated in opposite directions in alternate zonal divisions of the apparatus.

The invention also comprehends means 30 whereby the velocity of drying medium may be varied in the several zonal sections.

The structure whereby we attain these ends will be better understood from the detailed description which follows.

Figure I, is a side elevation of a drying machine conveniently embodying our invention.

Fig. II, is a cross sectional elevation of the same as viewed in the direction of the 40 arrows II—II, in Fig. I; and

Fig. III, is a plan sectional view of a portion of the machine.

Fig. IV, is a side elevation similar to Fig. I, of a modified form of our invention.

The structure herein represented 45 comprises an extensive inclosure 1, having the cross sectional configuration shown in Fig. II. The interior is arranged to provide a longitudinal main or drying chamber 2, which traverses the structure from end to end, and occupies a central position between auxiliary side compartments 3 and 4. A horizontal by-passage 5, separated from the main chamber 2, by a sub-ceiling 6,

serves to connect the side compartments 3 and 4. Compartment 3, is directly communicative with the main chamber 2, but the compartment 4, is distinctly separated from the latter by a vertical partition 7, which, at its top, joins the end of the sub-ceiling 6. A series of rotary fans 8, set in openings 9, of the vertical partition 7, are functional in circulating the air laterally of the structure in the general direction of the arrows in Fig. II, *i. e.*, across the main chamber 65 2, into the auxiliary compartment 3, from which it returns by way of the by-passage 5, to the back of the fans 8, in compartment 4. If desired the circulation may be obviously effected in the opposite direction by reversing the rotation of the fans. 70

The goods to be dried are progressed through the main chamber, in the direction of the arrows in Fig. III, preferably under the support of wheeled trucks 10, serially 75 arranged in parallel rows, and guided upon rails 12, traversing the structure longitudinally. At its ends, the chamber is provided with suitable doors 13, and 14, respectively, which may be of any approved design, so 80 as to be readily operable to permit the quick interchange of trucks. In the present instance, the capacity of the chamber 2, is such as to conveniently accommodate three rows of carrier trucks, but this number may 85 be obviously varied according to the exigencies of practice. The trucks are provided with transverse end walls 11, (see Fig. III), which, by alinement, coöperate to automatically divide the chamber 2, into 90 a series of cross channels. The air circulation is thus more definitely restricted to the lateral course shown by the arrows. In order to prevent short circuiting of the air beneath the truck floors, we have provided 95 the structure at the sides of the main chamber with longitudinally extending guards 15 and 16, the latter being extended horizontally to the fan partition as indicated at 17, in Fig. II.

As a means of heating the circulated air, steam pipe coils 18, 19, are provided at intervals along the length of the machine, and preferably at regions directly adjacent the sides of the main chamber so as to be as 105 close as possible to the outside series of the carrier trucks. These heating coils are separately regulatable by means of hand valves

20. Humidification devices 21, are similarly distributed along the length of the inclosure, preferably at the fan side, and likewise individually controllable by hand 5 valves 22.

In some instances, a machine constructed according to the principles so far set forth answers all practical purposes. In other words a structure in which the main chamber, the side compartment and the by-passage are co-extensive in forming a single comprehensive circulatory unit.

In other instances, for example in the treatment of china, porcelain or crockery products, in order to effect an even drying, it is especially desirable that the goods in passing through the machine, be subjected to the influence of the drying medium first from one direction and then from the other. 15 20 This condition we obtain primarily by rotating the fans in opposite directions, in alternate relation along the series, preferably in groups as best shown in Fig. I.

The driving system by which this is accomplished may be briefly described as follows:

An overhead drive shaft 25, transmits power through belts to a number of relay pulley shafts 26, which in turn drive directly the leading fan in each of the groups. The first four fans, at the right hand or receiving end of the machine, (Fig. I) are preferably driven in the same direction for a purpose which will be presently described. 30 35 The succeeding groups are alternately driven in opposite directions respectively by crossed and open belts 27 and 28, as clearly illustrated in Fig. I.

In order to positively restrict the circulation of the several fan groups to positive and definite zones, along the length of the apparatus, the auxiliary compartments 3, 4, and the connecting by-passage 5, have been subdivided by transverse partitions 29, 45 equally spaced preferably at distances corresponding to multiples of standard truck lengths, so that as the truck series are brought to a rest position within the drying compartment, said partitions always register with certain of the vertical ends 11, and in this way assist in the cross channeling of the structure.

From Fig. III, it will be further observed that the grouping of the individually controllable heating and humidifying devices is such that variously different atmospheric conditions may be maintained in the several zonal divisions of the structure.

In operation, as new units are added to the 60 truck series, the several rows are bodily advanced, thereby changing the positions of the preceding units. In this way the trucks are gradually advanced from one circulatory zone to another, and as a result the goods are subjected to the heated air currents first

from one side, and then from the other, as already understood from the previous description of the alternative arrangement of the circulating fans.

Referring once more to Fig. I, it will be noted that the first group of fans (right hand or receiving end) are of smaller diameter than the others. The circulation at this point is therefore rendered more sluggish, and as a consequence, a higher degree of 75 humidity may be maintained at the beginning of the drying operation, so that the initially introduced wet materials are given an opportunity to heat up very slowly preparatory to being advanced to regions of higher 80 temperatures in the succeeding zonal divisions of the apparatus. This provision acts to retard the drying of the outer surfaces of the material, so that the moisture may more readily work its way out from the interior. 85 This is of utmost importance in drying wares of the kind hereinbefore mentioned and serves to prevent the warping or cracking of the materials which usually results from unequal internal strains, caused by 90 uneven drying.

The same results as those just described may be obtained by using fans of the same diameter throughout the structure, but driving those of the initial zonal section at a 95 slower rate of speed.

Such a construction is shown in Fig. IV, where it will be seen that the fans 30, 30, in the initial zone section are of the same diameter as the fans 8, in the other portions of 100 the machine but driven at a slower rate of speed. This is accomplished by means of a belt 31, running over a small pulley on the shaft 25, and actuating a comparatively larger pulley 32, on the shaft of the end 105 fan. In this way, it will be seen that the air in the initial section of the zonal series is propelled at a very much slower rate than in the others so as to bring about the effect hereinbefore set forth.

Having thus described our invention, we claim:

1. A drying machine comprising an extensive inclosure having a longitudinal main chamber adapted to accommodate the articles 115 to be dried; a co-extensive auxiliary compartment at each side of the central or main chamber; and a co-extensive horizontal by-passage connecting said auxiliary compartments; in combination with propelling 120 means disposed at intervals along the length of the inclosure and adapted to circulate the air laterally thereof between the main chamber and the auxiliary compartments over zonal courses completed by the horizontal connecting by-passage.

2. A drying machine comprising an extensive inclosure having a longitudinal main chamber adapted to accommodate the articles to be dried; a co-extensive auxiliary

- compartment at each side of the main chamber; and a co-extensive horizontal by-passage connecting said auxiliary compartments; in combination with propelling means disposed at intervals along the length of the inclosure, and alternately arranged to circulate the air laterally thereof in opposite directions between the main chamber and the auxiliary compartments over zonal courses completed by the horizontal connecting by-passage. 5
3. A drying machine comprising an extensive inclosure having a longitudinal main chamber adapted to accommodate the articles to be dried; a co-extensive auxiliary compartment at each side of the central or main chamber; a co-extensive horizontal by-passage connecting said auxiliary compartments; and transverse partitions subdividing said auxiliary compartments and the connecting by-passage into a series of zonal sections lengthwise of the inclosure; in combination with individual means for circulating the air laterally through the main chamber within the confines of each zonal section. 10
4. A drying machine comprising an extensive inclosure having a longitudinal main chamber adapted to accommodate the articles to be dried; a co-extensive auxiliary compartment at each side of the central or main chamber; a co-extensive horizontal passage connecting said auxiliary compartments; transverse partitions subdividing said auxiliary compartments and the connecting passage into a series of zonal sections along the length of the inclosure; in combination with means for circulating the air in opposite directions in alternate zonal sections in a direction laterally of the inclosure and between the main chamber and the auxiliary side compartments. 15
5. A drying machine comprising an extensive inclosure subdivided into a main chamber adapted to receive one or more rows of trucks or carriers for the articles to be dried, said trucks having vertical ends by which the chamber is divided into a number
- of lateral channels; an auxiliary heating compartment at each side of the main chamber; a co-extensive horizontal by-passage connecting said auxiliary compartments; transverse partitions subdividing said heating compartments and the connecting by-passages into a series of zonal sections lengthwise of the inclosure, said partitions registering with certain of the vertical truck ends; in combination with individual means for circulating the air laterally of the machine within the confines of each of the zonal sections. 20
6. A drying machine comprising an extensive inclosure; means for dividing said inclosure lengthwise into a series of zonal sections through which the articles to be dried are successively passed; individual means for maintaining different degrees of heat and humidification in said zonal sections; means for circulating the air within the inclosure; and means whereby the circulation in the initial section of the zonal series may be rendered more sluggish than in the others, substantially as described and for the purpose set forth. 25
7. A drying machine comprising an extensive inclosure; means for dividing said inclosure lengthwise into a series of zonal sections through which the articles to be dried are successively passed; individual means for maintaining different degrees of heat and humidification in said zonal sections; and rotary fans for circulating the air in said zonal sections, the fans in the initial section of the series being of smaller diameter than the others, substantially as described and for the purpose set forth. 30
- In testimony whereof, we have hereunto signed our names at Philadelphia, Pennsylvania, this second day of September, 1919.
